UNITED STATES PATENT OFFICE

DANIEL E. HENNESSY, OF WATERTOWN, MASSACHUSETTS, ASSIGNOR TO LEWIS-SHEPARD COMPANY, OF WATERTOWN, MASSACHUSETTS, A CORPORATION OF MASSACHUSETTS

ELEVATING TRUCK

Application filed July 23, 1929. Serial No. 380,293.

This invention relates to improvements in elevating trucks comprising a frame and load supporting means connected by parallel links to said frame with means for raising the load supporting means relatively to the frame, whereby the parallel links will cause the load supporting means to move longitudinally relatively to the frame during the raising and lowering movement, and the principal object of the invention is to provide novel locking means for retaining the load supporting means in elevated position which can be readily released to permit the descent of the load.

15 The locking mechanism for elevating trucks of this type usually comprises interengaging hook-shaped members which can be disengaged only by the application of considerable force and frequently such locking members become broken.

In the present construction the locking mechanism comprises a shaft which is rotatably mounted on the load supporting means and a co-operating dog having a shoulder to engage said shaft when in locking position. Means are provided to rotate the shaft in a direction to cause the rolling engagement between said shaft and said shoulder to release the locking means. In order to insure positive locking of the load supporting means in elevated position the locking dog is so pivoted that the arc of movement of the shoulder thereof intersects the arc of movement of the shaft caused by the parallel links, so that when the parts are engaged relative longitudinal movement of the load supporting means is positively prevented until the shaft is rotated.

40 A further object of the invention is to provide an elevating truck comprising a frame and steering mechanism having a tongue mounted to swing vertically, with load supporting means mounted on parallel links upon said frame and having an integral lifting head overlying the steering mechanism, and a lifting lever operable by a vertical swinging movement of the tongue to apply vertically a lifting force to the lifting head in approximately the direction of the 45 axis of the steering mechanism, with means

for locking the load supporting means in elevated position, and a vertical dash pot within and protected by said lifting head having its cylinder and piston connected respectively to the frame, and load supporting means operable to cushion the descent of the load upon release of the locking means.

55 A further object of the invention is to provide a construction in which the locking mechanism and the dash pot, as well as the steering mechanism, are located substantially centrally of the longitudinal axis of the truck, and load supporting means, thereby preventing the application of twisting strains to either.

60 These and other objects and features of the invention will more fully appear from the following description and the accompanying drawings and will be particularly pointed out in the claims.

65 In the drawings:

Fig. 1 is a perspective view of a truck embodying the invention, viewed from the rear;

Fig. 2 is an enlarged perspective view of the front end portion of the elevating truck; and,

70 Fig. 3 is a detail view, partly in vertical longitudinal section, illustrating particularly the lifting mechanism, locking mechanism, and the dash pot.

75 The elevating truck embodying the present invention, as illustrated in the drawings, comprises a frame having a preferably integral head composed of arched members 1 and 2 which are spaced apart and connected by side members 3. These arched members are connected centrally of the width of the truck by an annular bridge 4 which desirably is integral with the head and in which the steering post of the steering mechanism is mounted.

80 The steering post is provided with downwardly extending yoke arms 5 having bosses to receive the axle 6 upon which the steering wheels 7 are mounted. A split collar 8 is rigidly clamped upon the upper end of the steering post and is provided with upwardly extending ears 9 in the upper end of which the pivotal shaft 10 for the steering tongue is mounted. The steering tongue comprises a curved base member 11 having a 85

bifurcated end portion, the arms 12 of which are mounted upon the shaft 10. The lifting lever comprises a preferably arcuate member 13 which is pivotally mounted upon the shaft 10 between the arms 12 and is provided at one end with a roller 14 movable substantially in the vertical direction of the axis of the steering post to engage a lifting head upon the load supporting means which will hereinafter be described. The other end of the member 13 is provided with a projection 15 adapted to be engaged by a co-operating member of a latch 16 which is pivotally mounted upon a shaft 17 extending through the arms 12 of the tongue. When the lifting lever and latch are thus engaged the lifting lever forms in effect an extension of the tongue, but when the latch is disengaged from the lifting lever the tongue is freed therefrom and can be moved vertically without actuating the lifting lever, thus permitting free movement of the tongue for steering purposes.

The construction of the lifting mechanism above described may be and desirably is substantially the same as that disclosed in my prior Patent No. 1,741,712, granted December 31, 1929.

Side bars 18, which are connected to the side members 3 of the head 1, extend rearwardly therefrom in parallelism and at their rear ends are connected by the rear axle 19 of the truck upon which the rear wheels 20 are mounted.

The load supporting means comprises side bars 21 which desirably overlie the side bars 18 of the frame and are connected at their rear ends by a channel bar 22 and at their front end by an integral lifting head comprising a front arched bar 23 and a rear plate 24 which are connected by side members 25. In proximity to the central longitudinal axis of the truck, parallel webs 26 and 27 extend upwardly from the plate 24 to the front arch 23 of the lifting head and are integral therewith. These webs are spaced apart sufficiently to provide a chamber for a vertical dash pot, the piston 28 of which is provided with ears 29 which are pivotally mounted upon a shaft 30 mounted in the webs 26 and 27. The cylinder 31 of the dash pot is supported upon and pivotally connected to a transverse girder 32 of the main frame.

By reason of this construction the dash pot is well protected from injury, and is located in the longitudinal central plane of the truck, so that when the weight of the load is imposed upon it, upon release of the locking mechanism, twisting strains will be avoided.

The lifting head 23 is provided with a forward extension 33 which overlies the axis of the steering post and has a flat under face 34 and is adapted to be detachably engaged

by the roller 14 upon the lifting lever when the tongue is depressed.

In operation, when the lifting lever is connected to the tongue by the latch 16, a downward swinging movement of the tongue will cause the roller 34 to engage the under flat face of the lifting head, and upon further continued downward movement will apply vertically a lifting force thereto substantially in the direction of the axis of the steering mechanism. Therefore, the front end of the load supporting means will be raised, and as it is raised will be caused to move longitudinally of the frame by reason of the parallel link connection thereto, so that the flat face 34 of the lifting head will ride upon the roller 14 during the lifting movement, thus enabling the lifting force to be applied vertically throughout the entire lifting movement.

The operation of the lifting mechanism is practically the same as that disclosed in my prior Patent No. 1,741,712 aforesaid.

One of the principal features of the invention relates to easily releasable mechanism for locking the load supporting means in elevated position. In the preferred construction illustrated herein this locking mechanism comprises a shaft 35 which is journalled in bearings in forwardly projecting portions of the webs 26 and 27 of the lifting head, and also desirably journalled in bosses 36 extending rearwardly from the arch 23, and a co-operating locking dog 37 which is provided at its upper end with a flat shoulder 38 to engage the shaft 35, and a preferably integral extension 39 to engage the front side of the shaft in such a manner as to prevent the dog from passing therebeneath. The lower end of the dog 37 is provided with cylindrical extensions 40 which are journalled in suitable bearings 41 and 42 upon the head of the frame. Desirably the bearing 41 is open at its top to permit the insertion of the cylindrical extension 40 in the other bearing 42. One of the extensions 40 projects beyond the bearing 42 and has coiled upon and secured to it a spring 43, the end 44 of which extends across and engages the dog 37 and acts to hold the dog at all times in engagement with the shaft 35. Upon upward movement of the load supporting means the shaft 35 is carried upwardly until it passes the shoulder 38 upon the dog when the end 44 of the spring 43 will force the upper end of the dog rearwardly so that the shoulder 38 will engage beneath the shaft, thereby locking the load supporting means in elevated position.

The locking dog 37 is so pivoted upon the main frame that the arc of its movement shown by the dotted line *a* in Fig. 3 intersects the arc of movement of the shoulder of the dog shown by the dotted line *b* at substantially the line of engagement between the shoulder 38 and the shaft 35, so that rear-

ward downward movement of the load supporting means is prevented while the locking dog is thus positioned.

While the engagement between the shoulder 38 of the locking dog 37 and the shaft 35 provides a positive lock it can be easily released by rotation of the shaft 35. The shaft 35 is provided with a pedal 45 which desirably extends upwardly in convenient reach of the operator and may be pushed backwardly by his foot. The rotation imparted to the shaft by such movement of the pedal 45 is in a direction to cause the rolling engagement between the shaft 35 and the shoulder 30 readily to move the upper end of the locking dog forwardly until the shoulder 38 is released from the shaft, thus permitting descent of the load supporting means. The spring 46, which, as illustrated herein, is secured at its upper end to a pin 47 extending from the shaft 35 and at its lower end to a pin 48 on the frame member 2, serves to restore the pedal to normal position in which it rests against the arch 23 of the lifting head.

Rapid descent of the load supporting means is prevented by the dash pot which is interposed between the lifting head and frame.

The construction of the truck above described is of a very simple but rigid character. Such trucks can be constructed to carry very heavy loads and can be easily operated both to raise the load supporting means when loaded and to release the locking means when the load is supported in elevated position.

It will be understood that the particular embodiment of the invention described herein is of an illustrative character and is not restrictive, and that various changes in form, construction and arrangement of parts may be made within the spirit and scope of the following claims.

Having thus described the invention, what is claimed as new, and desired to be secured by Letters Patent, is:

1. An elevating truck comprising a frame, load supporting means, means for raising said load supporting means including parallel links acting to cause longitudinal movement of said load supporting means relatively to said frame during the raising and lowering movements thereof, a shaft rotatably mounted upon said load supporting means, a dog pivotally mounted on said frame having a shouldered free end positioned to engage said shaft when the load supporting means is raised to a predetermined height and thereby to lock said load supporting means against descent, and means for rotating said shaft in a direction to cause the rolling engagement with said shoulder to release the dog therefrom.

2. An elevating truck comprising a frame, load supporting means, means for raising said load supporting means including parallel links acting to cause longitudinal move-

ment of said load supporting means relatively to said frame during the raising and lowering movements thereof, a shaft mounted on the front end of said load supporting means, a dog pivotally mounted on said frame having a shoulder to engage said shaft and so positioned that the arc of movement of the shoulder thereof will intersect the arc of movement of said shaft caused by said parallel links at substantially the line of engagement of said shaft and shoulder, and means for rotating said shaft in a direction to cause the rolling engagement with said shoulder to release the dog therefrom.

3. An elevating truck comprising a frame, load supporting means, means for raising said load supporting means including parallel links acting to cause longitudinal movement of said load supporting means relatively to said frame during the raising and lowering movements thereof, a shaft mounted on the front end of said load supporting means having at its end a pedal, a dog pivotally mounted on said frame having at its upper end a shoulder to engage said shaft, and an extension therefrom to prevent movement of said shoulder beyond said shaft, means pivotally connecting the lower end of said dog to said frame so positioned that the arc of movement of said shoulder will intersect the arc of movement of said shaft caused by said parallel links at substantially the line of engagement of said shoulder and shaft, means acting to hold said dog in engagement with said shaft, a pedal on said shaft operable to rotate said shaft in a direction to cause the rolling engagement with said shoulder to release the dog therefrom, and resilient means acting to rotate said shaft in the opposite direction upon release of said pedal.

4. An elevating truck comprising a frame, steering mechanism having a tongue mounted to swing vertically, load supporting means having an integral lifting head overlying said steering mechanism, parallel links connecting said load supporting means to said frame, a lifting lever operable by a vertical swinging movement of said tongue to apply vertically a lifting force to said lifting head in approximately the direction of the axis of said steering post, a shaft rotatably mounted on said lifting head, a dog pivotally mounted on said frame having a shoulder to engage said shaft and so positioned that the arc of movement of said shoulder will intersect the arc of movement of said shaft caused by said parallel links at substantially the line of engagement of said shaft and said shoulder, means for releasing the lifting means from operative relation to the tongue, and means for rotating said shaft in a direction to cause the rolling engagement with the shoulder to release the dog therefrom.

5. An elevating truck comprising steering mechanism having a tongue mounted to

swing vertically, load supporting means having an integral lifting head overlying said steering mechanism, a lifting lever operable by a vertical swinging movement of said tongue to apply vertically a lifting force to said lifting head in approximately the direction of the axis of said steering mechanism, means for locking the load supporting means in elevation, means for releasing said lifting lever from operative relation to said tongue, a vertical dash pot located within said lifting head centrally of the width of the truck having a cylinder and piston connected respectively to said frame and said lifting head, and means for releasing said locking mechanism.

6. An elevating truck comprising a frame, steering mechanism having a tongue mounted to swing vertically, load supporting means having a lifting head integral therewith overlying said steering mechanism, parallel links connecting said load supporting means to said frame, a lifting lever pivotally mounted upon said steering mechanism forming an extension of said tongue and having means to engage and apply vertically a lifting force to said lifting head in approximately the direction of the axis of said steering mechanism, means releasably connecting said lifting lever to said tongue whereby said lifting lever may be actuated by a vertical swinging movement of the tongue to lift the load supporting means, or released to permit free steering movement of the tongue, a shaft mounted in said lifting head, a dog pivotally mounted upon said frame having a shouldered upper end to engage said shaft and lock the load supporting means in elevated position, and a pedal connected to said shaft operable to rotate the shaft in a direction to cause the rolling engagement with said shoulder to release said dog.

7. An elevating truck comprising a frame, steering mechanism having a tongue mounted to swing vertically, load supporting means having a lifting head integral therewith overlying said steering mechanism, parallel links connecting said load supporting means to said frame, a lifting lever pivotally mounted upon said steering mechanism forming an extension of said tongue and having means to engage and apply vertically a lifting force to said lifting head in approximately the direction of the axis of said steering mechanism, means releasably connecting said lifting lever to said tongue whereby said lifting lever may be actuated by a vertical swinging movement of the tongue to lift the load supporting means, or released to permit free steering movement of the tongue, a shaft mounted in said lifting head, a dog pivotally mounted upon said frame having a shouldered upper end to engage said shaft and lock the load support-

ing means in elevated position, a pedal connected to said shaft operable to rotate the shaft in a direction to cause the rolling engagement with said shoulder to release said dog, and a dash pot having a cylinder and piston connected respectively to said frame and said lifting head and located within said lifting head and protected thereby operable to cushion the descent of the load upon release of said locking dog.

In testimony whereof, I have signed my name to this specification.

DANIEL E. HENNESSY.
